UNITED STATES PATENT OFFICE

2,246,093

PROJECTION OF PICTURES IN COLORS

Otto C. Gilmore, Van Nuys, Calif., assignor to
 Cosmocolor Corporation, Jersey City, N. J., a
 corporation of Delaware

Application October 27, 1937, Serial No. 171,311

20 Claims. (Cl. 88—16.4)

This invention relates to the art of color photography and more particularly to the projection of moving pictures in color. Specifically, the present invention is concerned with the projection of pictures in color from films upon which the color values of the scenes photographed are represented in two or more black and white images lying within a single frame.

Prior to the present invention a number of attempts have been made to find a satisfactory means for projecting pictures in color from films of the type mentioned and these attempts are typically illustrated by Patent 1,262,954, granted to F. E. Ives in 1918, by Patent 1,350,143, granted to F. W. Donisthorpe in 1920, by Patent 1,631,866, granted to Anton Heurung in 1927, and by Patent 2,050,224, granted to the present inventor in 1936. United States Patent No. 2,152,959 granted to this same inventor, is also concerned with this same problem. A casual inspection of the patents mentioned will furnish a rather complete history of the development of the particular type of device here involved.

In the design of devices of the type to which the present invention relates many problems have been encountered. The projections from the several images on the film must be undistorted and of exactly the same size and geometrical configuration when they reach the screen. They must all focus at the screen and furthermore they must represent color values which will combine to produce on the screen an accurate and pleasing reproduction of the color of the original scene. The device used for the projection must be relatively simple to adjust and simple in operation and one that does not absorb or cut off any appreciable amount of the light intended for the screen. This inventor has discovered that in order to obtain ready acceptance of his process it is also highly desirable that his device be in the form of an attachment which can be readily inserted in the ordinary theatre projector in place of the ordinary projection lens. By the arrangement of parts hereinafter described the inventor has succeeded in satisfying the many conditions necessary to the satisfactory projection of pictures of this type and at the same time has provided a device in the form of an attachment that will do all these things and which, in addition, can be quickly and easily substituted for the ordinary projector lens in the theatre projectors now in common use.

The basic elements of the optical system of the device of the present invention are the same as those described in this inventor's United States

Patent No. 2,152,959; that is, they comprise from the film towards the screen in the order named, a completely separate objective and color filter for each of the images on the film and a turning prism means. The latter may be a separate prism for each image on the film or a single prism which turns all of the images. By the use of a completely separate objective lens for each of the images, the problem of focusing and registering has been found to be greatly simplified and the passage of stray light from one image pencil into the other in the lens set has been entirely eliminated. The elimination of other parts of the optical system, which this inventor has found unnecessary, adds greatly to the efficiency of the system and to the sharpness, clarity and brightness of the projected pictures.

The color filters may be placed on either side of the objective lenses or between the elements of these lenses. A part of this invention resides in the discovery of a particular combination of colors, which when used in these color filters will produce exceptional and unusually good results in the projected pictures. When projecting from a film having two images to the frame, filters corresponding to Wratten filter No. 28, cine red, and Wratten filter No. 38, toluidine blue, have been found to be far superior to pictures projected through any other combination of filters known to this inventor. The picture projected through the No. 28 filter should preferably have been taken through a filter similar to a Wratten No. 22 red filter and the image projected through the No. 38 filter should have been taken through a filter corresponding to a Wratten filter No. 59, projection green, if taken in sunlight, a Wratten filter No. 59A, projection green (light), if taken in incandescent light, and a No. 60P Wratten filter if taken in arc light.

Although the filters may be in the form of a gelatin film cemented between optical glass, it has been found preferable to use heat resisting Corning glass of the same color. In projection, the heat generated by the source of light is so great that gelatin film filters are likely to be injured.

Another improvement in the present device is found in the manner in which the objectives are mounted. As shown in United States Patent No. 2,152,959, both objectives are shiftable in a plane normal to the light beam. It has now been found that by definitely fixing the position of one of the two objectives and making the other objective movable in two directions in the plane normal to the light beam, a definite advantage

results. The objective that is permanently fixed is, of course, placed directly in front of and in line with the image that it is to focus on the screen. Being fixed, it remains in this position and there is no possibility of adjusting it to a position where it will not be in correct alignment and cause distortion. The movable objective, being adjusted so as to cause its image to register with the image of the fixed objective, is necessarily adjusted at all times to about the same position, and never has an opportunity to get very much out of line with the image on the film.

Another feature of the present invention is the arrangement by which the light from the two separate images is prevented from diffusing from one image bearing light pencil into the other during the passage of the light pencils from the images on the film through the objective lenses. This arrangement includes completely separate objective lens systems and other structural arrangements. The completely separate lens systems have the added advantage of permitting the lens systems to be individually positioned and advantage has been taken of this fact to position the lens systems differently so as to compensate for the difference in the color of the light which they focus on the screen. In other words since blue is refracted to a greater extent than red the lens system for the blue is positioned farther from the film to cause the blue image to focus in the same plane as the red.

The arrangement which completely separates the light beams also comprises a telescopic hood mounted in the rear end of the main housing and resiliently pressed towards the film gate of the projector. It also includes a septum or a dividing fin mounted in the telescopic hood so as to extend from the film gate forward to a position between the objective lenses. At this point the septum cooperates with diaphragms or additional septums which cover the adjacent sides of the objective lens systems and form between them a slot in which the end of the movable septum may slide. The movable septum is slightly warped so as to completely fill the slot and because of this arrangement no light can pass through the slot and into the turning prism, or from one light beam into the objective intended for the other light beam.

A still further improvement that it has been found desirable to incorporate in the present device is a series of baffles which surround the path of the image bearing light beams between the objectives and the turning prism means. These baffles act to intercept any stray light from the objectives and absorb or turn it back so that it cannot enter the turning prism.

Besides these improvements the present invention also includes means for quickly and easily positioning the new lens system in place of the usual projection lens, in two of the more common types of projection machines. At the present time, many theatres are equipped with a type of projector known as the Standard Simplex projector manufactured by the International Projector Corporation. In order to replace the projection lens in such a projector by the lens system of this invention, it is necessary to loosen the lens clamp, remove the lens, place the new lens device in the clamp, adjust it to the desired position, and tighten the clamp. This seems simple enough, but in practice it is quite difficult to accomplish because the new lens system must be positioned, axially, just far enough in the projector so that it will be substantially in focus, 75

and at the same time the new lens system must be rotated about its axis to a position where the base of the turning prism will be at an angle of exactly 45° to the horizontal so that it will act properly to turn the images into their upright position. In order to provide a means for accomplishing this positioning with a minimum loss of time and with maximum accuracy, the present invention provides means mounted on the housing of the projector and additional means mounted on the lens attachment which are engaged when the device is first placed in the projector and serve to position the device accurately. These means are then released from their engagement so that the normal focusing mechanism of the projector can make the final adjustment to bring the picture to maximum sharpness on the screen.

Another type of projector that is now in extended commercial use is known as the Super 20 Simplex projector. This projector is likewise manufactured by the International Projector Corp. The present invention also includes an arrangement of parts by which the optical system of this invention may be inserted into this 25 type of projector with the same ease and certainty as the arrangement already mentioned provides in the case of the Standard Simplex projector. The arrangement of parts in the case of the Super Simplex projector includes an outer 30 shell which surrounds the main housing of the device of this invention. This shell is of such a size that it may be readily clamped in the two lens clamps of the projector. At the forward end of this shell is a positioning ring so constructed as to clamp tightly onto the shell and cooperate with parts already present on the projector to accurately position the device in the lens clamps.

Other improvements embodied in the present 40 invention will be apparent from the appended drawings and the following detailed description of the specific embodiments of this invention shown in the drawings.

In the drawings: 45 Fig. 1 is a side view of a part of a Standard Simplex projector, partly cut away to show the device of the present invention in place therein;

Fig. 2 is a front view of the same part of a projector that is shown in Fig. 1;

Fig. 3 is a rear end view of the device of this 50 invention, showing the telescopic hood that cooperates with the film gate of the projector;

Fig. 4 is a partial side view of the device of this 55 invention, taken along the line 4—4 of Fig. 3, partially in section so as to show the arrangement of the objective lenses and the telescoping hood;

Fig. 5 is a sectional view of the remainder of the 60 device of this invention taken on line 5—5 of Fig. 2;

Fig. 6 is a bottom sectional view of the part 65 of the device shown in Fig. 5, the section being taken along the line 6—6 of Fig. 5;

Fig. 7 is a sectional view of the device of this 70 invention taken along the line 7—7 of Fig. 4 and looking toward the forward end of the device;

Fig. 8 is a top sectional view of the same part 75 of the device as is shown in Fig. 4, taken along the line 8—8 of Fig. 4 and showing the telescoping hood pressed further into the housing than in Fig. 4;

Fig. 9 is an axial section of the device taken on line 9—9 of Fig. 5 and looking toward the rear of the device;

Fig. 10 is a similar view taken on line 10—10 of Fig. 1;

Fig. 11 is a similar view taken on line 11—11 of Fig. 4;

Figs. 12, 13 and 14 together constitute an expanded view of the interior parts of the device;

Fig. 15 is a sectional detail view of the device shown in Fig. 5 and is taken along the line 15—15 of that figure, looking in an axial direction toward the rear of the device;

Fig. 16 is a side view of a part of a Super Simplex projector, parts of which have been cut away to show a device embodying the principles of the present invention in place therein;

Fig. 17 is a front view of the same part of a projector as shown in Fig. 16;

Fig. 18 is a partial side view partially in section of the modification of the device of the present invention which is suitable for use in a Super Simplex projector and is taken along line 18—18 of Fig. 17. This figure also shows a part of the projector clamps of the projector in the position that they occupy when the device of the present invention is in place in a projector;

Fig. 19 is a bottom view of a part of the device shown in Fig. 18, with parts cut away to show the arrangement of the objective adjusting rods. It has been taken along line 19—19 of Fig. 17;

Fig. 20 is an axial sectional view taken along the line 20—20 of Fig. 18 and looking toward the rear of the device;

Fig. 21 is a spectrophotometric absorption curve of a #28 Cine Red Wratten filter;

Fig. 22 is a similar curve for a #38 Toluidine Blue Wratten filter;

Fig. 23 is a similar curve for a #22E2 Red Wratten filter;

Fig. 24 is a similar curve for a #59 Projection Green Wratten filter;

Fig. 25 is a similar curve for a #59A Projection Green (light) Wratten filter;

Fig. 26 is a similar curve for a #60P Wratten filter.

As shown by the drawings, and particularly by Figs. 4 and 5, light from the projection light in the projector, after passing through a film which has two images within each frame, enters the device of this invention through the opening 30 in the telescopic hood 31. This hood is telescopically mounted in a cylindrically shaped main casing 32 and is guided by rods 33 and 34 which are fixed rigidly in the lens support 35 which in turn is fastened to the main housing 32. The guide rods 33 and 34 are received in sleeves 36 and 37 rigidly fixed in the telescopic hood and coil springs 38 and 39 surround the rods and sleeves, bearing against the hood on one end and the main lens support 35 on the other, so as to press the hood outward against the film gate of the projector. As can be seen from Fig. 8, a cap screw 40 in the side of the hood 31 cooperates with a slot 41 in the main housing to limit the movement of the hood with respect to the housing so that this device will not come apart when it is removed from the projector. In addition, a part of the telescopic hood is cut away and covered with a small plate 42 affixed with screws 43 so as to avoid interference with the mechanism of the projector.

Upon entering the device shown in the drawings, the beams or pencils of light proceed directly to their respective objective lens systems 44 and 45. Each of these lens systems includes a pair of compound lenses 46 and a color filter 47. The lenses of each set are mounted in primary carry-

ing members 48. The lenses are held in place in the primary carrying members by retaining rings 49 and 50, the ring 50 being toward the rear of the device and having the color filter mounted in it. A sub-retaining ring 51 functions to hold the color filter in the lens retaining ring 50.

The primary carrying members 48 and the retaining rings 49 and 50 extend only part way around the lenses and leave the adjacent sides of 10 the two objective lens systems, 44 and 45, exposed. These sides are covered by diaphragms or septums 52 and 53 so as to prevent the diffusion of light from one objective lens set into the other. As an additional preventative against the diffusion of light from one light beam into the other, a septum 54 is mounted in the telescopic hood and extends from the entrance to the hood to a point well between the diaphragms 52 and 53. The septum 54 is slightly warped at the place 20 where it extends between the diaphragms so that it will at all times tightly close the gap between the diaphragms and seal this gap so that no light can pass through it.

As shown in Fig. 4, one of the primary lens carriers is mounted directly and rigidly fixed in the main lens support 35. This objective never moves relative to the main housing of the device. The other primary lens carrier, however, is mounted in a movable carrier 55 which is in turn 30 slidably mounted on a transversely movable member 56, which again in turn is slidably mounted on the prism retaining frame 57, which is fixed to the main housing 32 by screws 57a. The slideable mounting in each case is of the tongue and 35 groove type and the mountings are so arranged that the transversely movable member 56 can slide transversely on the prism retaining member 57, carrying with it the movable lens mounting 55, which can also slide on the member 56 40 and move vertically with respect thereto.

In order to actuate the transversely movable member and the movable lens carrier, rods 58 and 59, shown in Figs. 13 and 14 are provided, the rods carrying eccentrically mounted hardened rollers 60 and 61 on their rearwardly extending ends and short levers 62 and 63 on their forward ends. The rod 59 is rotatably mounted in an opening 64 in the prism retaining frame 57 so that the hardened roller 61 will enter a slot 65 in the transversely movable member and will operate upon rotation of the rod to shift that member in a transverse direction. The rod 58 is mounted in another opening 66 in the prism retaining frame 57, and is also free for rotation. 55 This rod passes through an opening 67 in the transversely movable member 56 and the roller 68 on this rod engages a slot 68 in the movable lens carrier 55. Upon rotation of the rod 58 the roller 60 acts to move the movable lens carrier 60 55 in a vertical direction.

In order to maintain the movable members 55 and 56 against the prism retaining ring 57, a spring retaining ring 69 has been provided as shown in Fig. 5. This ring is fastened by screws 65 70 to the main lens support 35 and presses against the movable lens carrier 55.

From the objective lens system, the two beams or pencils of light pass through an opening 71 in the prism retaining frame and to a dove prism 72. The edges of the opening 71 are of a saw-tooth cross section with the points directed rearwardly so as to form a series of baffles 72a which catch any stray light that passes through the objective lens system and either absorb this light or reflect it back and away from the prism. The 75

prism retaining frame 57 is so constructed as to hold one of the lower corners of the prism and also, with the help of a cork retaining member 13, a washer 14 and a screw 15 holding these members to the frame, to hold in position the upper corner of the prism. In addition, the prism retaining ring 57 includes a hood member 76 which surrounds the incoming light beams and prevents light which may be reflected from the face of the prism from diffusing around the prism. The other lower corner of the prism is supported by a supporting member 77 attached to the main housing 32 by a pin 78 and screws 79.

In the embodiment of the new device that is adapted to fit into a Standard Simplex projector, a cap 80 of the type shown in Figs. 5 and 6 covers the forward end of the main housing 32. This cap which is held in place by screws 81 has an opening 82 through which the image-bearing light pencils pass to the screen, and also has two smaller openings 83 and 84 which receive the forward end of adjusting rods 58 and 59 respectively.

In order to prevent the adjustment of the device from changing after it has been set, a brake is provided for the two adjusting rods as shown in Figs. 5, 6 and 10. This brake consists of a cross bar 85 through which both of the adjusting rods 58 and 59 pass. A screw 86 connects the cross bar to the cap 80, and when this screw is tightened the cross bar is drawn toward the cap so as to bear tightly against the levers 62 and 63 on the adjusting rods.

The arrangement whereby this device may be readily mounted on a Standard Simplex projector consists of an annular member 87 which takes the place of the annular member which ordinarily surrounds the lens opening in the front of the projector. The annular member used according to this invention however carries a forwardly extending lug 88 which is arranged to engage and position a ring shaped clamping member 89 which is permanently mounted on the new projection device by means of bolts 90 which span a split side of the ring. The ring is so designed as to have an outwardly extending arm 91 shaped so as to receive the end of the positioning lug 88 and a thumb screw 92 is carried by this arm and received in a threaded opening in the lug 88 so as to clamp the arm in position against the lug. In this position, the lug 88 partially enters a recess in the arm so that the position of the ring 89 and the new projection device is accurately fixed. To hold the bolt 92 at all times in the upper position in the arm 91, a spring 93 is provided within the opening in the arm through which the bolt passes. This spring surrounds a part of the bolt and one end presses against the arm while the other presses against a small retaining ring 94 affixed to the bolt. In this manner, the spring constantly urges the bolt further into the opening in the arm so that the head of the bolt is kept constantly against the arm. The bolt, however, is free to move yieldably when the arm is against the positioning lug.

As can be seen from Fig. 1 this positioning lug is preferably constructed separately from the annular member 87 and is connected thereto by means of a pin 95 which passes through the positioning lug 88 and also through two small lugs 96 which are part of the annular member and one of which lies on each side of the positioning lug. The part of the arm 91 which is immediately in contact with the positioning lug is also made separately from the remainder of the

arm and as shown in Fig. 1 is merely pressed tightly into an opening in the arm.

In operation, the device of the present invention is placed in the projector from the front end and moves axially toward the rear until the bolt 92 engages the annulus 87 through its positioning lug 88 and the arm 91 on the ring. The bolt 92 is then tightened in the lug 88 and the device is in its initial position in the projector. The projector clamp 97, shown in Fig. 1, is then tightened on the housing 32 and the bolt 92 loosened to permit focusing adjustments of said device. The device is now ready for operation. Adjustment may be made to register the image on the screen by moving the small levers 62 and 63 and final focusing may be accomplished by the usual focusing mechanism of the projector.

When the device of the present invention is to be used with a Super Simplex projector, the cap 80 is replaced by an adapter shell 98 which encloses the whole forward end of the main housing 32 and extends forward for a short distance beyond the housing. It is connected to the housing by bolts 98a. The adjusting rods 58 and 59 are somewhat longer than they are in the model already described but are received in the adapter shell in much the same manner that they are in the cap 80 and carry similar levers on their forward ends. A plate 99 fastened to the adapter shell by screws 100, 101 and 102 serves as a brake to prevent accidental rotation of the shafts. The screw 101 acts to draw this plate down tightly against the ends of the rods to prevent movement.

A positioning ring 103 is clamped around the adapter shell nearest the forward end by means of a thumb screw 104 spanning a split side. This ring carries an arm 105 which cooperates with a forwardly extending shaft 106 already on the projector and also has an opening 107 which fits over a forwardly extending shaft 108 also already a part of the projector. By means of these two arrangements, the rotative position of the new optical system is accurately fixed, and the ring 103 is so placed on the shell that the axial position of the device will be fixed by pressing the device back into the projector until the ring 103 rests against the forward lens holding clamp 109 of the projector. Once the device is in this position both the forward clamp 109 and a rear clamp 110 are tightened on the device and final adjustment may be made by the usual focusing mechanism and the small registering levers 62 and 63.

While the particular constructions which make the present device readily adaptable for use with two of the most commonly used projectors are definitely a part of this invention, it is to be understood that the principles of the invention may be applied more broadly and that the invention is therefore not limited to this particular embodiment.

I claim:

1. In a device for projecting two pictures in superposed relation upon a screen, from a film on which the two pictures appear in side by side relation and on their sides within a single frame, the combination of two completely separate objective lens systems, one for each image, erecting prism means for turning both images into their upright positions, and baffles surrounding the path of the light beams between the objective lens system and the erecting prism means, said baffles being arranged to prevent

the passing of stray light from the lens systems to the erecting prism means.

2. A device for projecting pictures in color from black and white films carrying color records that comprises two completely separate objective lens systems arranged to project images from two separate records, color filters positioned so as to filter the light that passes through each of said objective lens systems, means for holding one of the objective lens systems in a fixed position, and means for shifting the other objective lens system in a plane normal to the light passing therethrough and in two directions substantially at right angles to each other, erecting prism means for turning both images into their upright positions, baffles surrounding the path of the light beams from the records between the objective lens systems and the erecting prism means, said baffles being arranged to prevent the passing of stray light from the lens systems to the erecting prism means, a mask for each objective lens system positioned along the side of the lens system which lies adjacent the other lens system so as to completely shield its lens system against the entrance of stray light from the other system, an axially movable septum arranged to extend from a point close to the film to a point between the masks and completely separate the light beams from the respective records, said septum being slightly warped at a point between the masks so as to completely close the slot between them and allow no light to pass therethrough, a cylindrical housing for said parts, a positioning means associated with said housing and arranged so as to cooperate with parts of a standard type of motion picture projector to locate the parts within said housing in a predetermined position with respect to said projector, and means to secure said housing in said predetermined position to the casing of the projector.

3. In a projection device the combination of two completely separate objective lens systems, a mask for each objective lens system positioned along the side of the lens system which lies adjacent the other lens system, so as to completely shield its lens system against the entrance of stray light from the other system, a housing to enclose said parts, a hood telescopically mounted on said housing means for resiliently urging said hood from said housing, and an axially movable septum supported by said hood and arranged to extend from a point close to the film to a point between the masks and completely separate the light beams from the respective pictures.

4. A device for projecting a pair of images which are carried by a support on to a screen in registration, comprising a housing, a separate objective system for focusing each image upon the screen, a prism means for turning the images separate supports within said housing for said objective systems and said prism means, said prism support being provided with a series of baffles to prevent the passing of stray light to said prism means, one of said objective systems being mounted in a fixed support, the other of said objective systems being mounted within a movable support, shields carried by said objective supports to prevent the diffusion of light between said systems, a telescopic hood supported by said housing and arranged to resiliently extend from said housing toward said film, and an axially movable septum supported by said hood and arranged to extend between said shields

to prevent the diffusion of light from one image beam into another, said septum being bent at a point between the shields so as to resiliently close the slot therebetween regardless of the distance between said shields and thereby prevent the passing of stray light to said prism means.

5. A device for projecting images which are carried by a transparency on their sides on to a screen in registration, a housing, a separate objective system for focusing each image upon the screen, prism means for erecting said images during projection, separate supports within said housing for said objective systems and said prism means, said prism support being arranged to locate said prism means in a predetermined position within said housing, one of said objective systems being mounted in a fixed support, the other of said objective systems being mounted within a movable support, means carried by said prism support to control the adjustment of said movable objective support whereby to adjust said objective system with respect to its companion objective system and to said prism means, and positioning means carried by said housing and arranged to cooperate with parts of a standard type of motion picture projector to locate said housing in a predetermined position with respect to said projector.

6. A device for projecting a pair of images which are carried by a transparency on their sides on to a screen in registration, a housing, a separate objective system for focusing each image upon the screen, a prism means for erecting said images during projection, separate supports within said housing for said objective systems and said prism means, said support for said prism means being arranged to locate said prism means in a predetermined position within said housing, one of said objective systems being mounted in a support fixed to said prism support to locate said objective in a predetermined position with respect to said prism means, the other of said objective systems being mounted within a movable support carried by said prism support, means carried by said prism support to control the adjustment of said movable objective support whereby to adjust said objective system with respect to its companion objective system and to said prism means.

7. A device for projecting a pair of images which are carried by a transparency on their sides on to a screen in registration, a housing, a separate objective system for focusing each image upon the screen, a prism means for erecting said images during projection, separate supports within said housing for said objective systems and said prism means, said support for said prism means being arranged to locate said prism means in a predetermined position within said housing and including a series of baffles to prevent the passing of stray light to said prism means, one of said objective systems being mounted in a support fixed to said prism support to locate said objective in a predetermined position with respect to said prism means, the other of said objective systems being mounted within a movable support carried by said prism support, means carried by said prism support to control the adjustment of said movable objective support whereby to adjust said objective system with respect to its companion objective system and to said prism means, shields carried by said objective supports to prevent the diffusion of light between said systems, a telescopic hood supported by said housing and arranged to resiliently ex-

tend from said housing toward said film, an axially movable septum supported by said hood and arranged to extend between said shields to prevent the diffusion of light from one image beam into the other, said septum being bent at a point between the shields so as to resiliently close the slot therebetween regardless of the distance between said shields and thereby prevent the diffusion of light to said prism means, positioning means carried by said housing and arranged to cooperate with parts of a standard type of motion picture projector to locate said housing in a predetermined position with respect to said projector, and clamping means to secure said housing thereto in said predetermined position.

8. A device for projecting images in pairs comprising an apparatus for handling film, two completely separate objective lens systems, one for each image beam, erecting prism means for turning both image beams one of said objective lens systems being movably mounted to permit differential adjustment with respect to the other objective lens system, a mask for each objective lens system to prevent the diffusion of light between the systems, and a septum arranged to extend from a point close to the film to a point between the masks to prevent diffusion between the image beams, said septum being bent at a point between the masks so as to resiliently bear against the opposed surfaces of said masks and close the space between the masks regardless of the distance therebetween and thereby prevent the passing of stray light through said space to said prism means.

9. In a device for projecting two pictures in superposed relation upon a screen, from a film on which the two pictures appear in side by side relation and on their sides within a single frame, the combination of two completely separate objective lens systems, one for each image, erecting prism means for turning both images into their upright positions, a support for said prism, and baffles carried by said prism support and surrounding the path of the light beams between the objective lens systems and the erecting prism means, said baffles being arranged to prevent the passing of stray light from the lens systems to the erecting prism means.

10. In a projection device the combination of two completely separate objective lens systems, a mask for each objective lens system positioned along the side of the lens system which lies adjacent the other lens system, so as to completely shield its lens system against the entrance of stray light from the other system, a housing to enclose said parts, a hood telescopically mounted on said housing, cooperating guide means carried by said housing and said hood, resilient means located by said guide means for urging said hood from said housing, and a septum carried by said hood to extend from a point close to the film to a point between the masks and completely separate the light beams.

11. In a projection device the combination of two completely separate objective lens systems, a mask for each objective lens system positioned along the side of the lens system which lies adjacent the other lens system, so as to completely shield its lens system against the entrance of stray light from the other system, a housing to enclose said parts, guide rods mounted on said housing, a hood telescopically mounted on said housing, guide sleeves carried by said hood for telescopically receiving said guide rods, helical springs surrounding said guide sleeves and guide

rods for resiliently urging said hood from said housing, and a septum carried by said hood to extend from a point close to the film to a point between the masks and completely separate the light beams.

12. A device for projecting images which are carried by a transparency on their sides on to a screen in registration, a housing, separate objective systems for focusing said images upon the screen, prism means for erecting said images during projection, separate supports within said housing for said objective systems and said prism means, said prism support being arranged to locate said prism means in a predetermined position within said housing, one of said objective systems being mounted in a fixed support, the other of said objective systems being mounted within a movable support, and means carried by said prism support to control the adjustment of said movable objective support whereby to adjust said objective system with respect to its companion objective system and to said prism means.

13. A device for projecting a pair of images which are carried by a transparency on their sides on to a screen in registration, a housing, separate objective systems for focusing each image upon the screen, a prism means for erecting said images during projection, separate supports within said housing for said objective systems and said prism means, said support for said prism means being arranged to locate said prism means in a predetermined position within said housing, one of said objective systems being mounted in a support fixed to said prism support to locate said objective in a predetermined position with respect to said prism means, the other of said objective systems being mounted within a support which is movably mounted on said prism support, adjusting means carried by said prism support whereby to adjust said objective system with respect to its companion objective system and to said prism means, and means carried by said housing for locking said adjusting means to retain the movable objective system in adjusted position.

14. A projection device comprising a photographic apparatus having a lug extending therefrom, two separate objective systems and a turning prism means with a housing therefor, the parts of said optical system being mounted in predetermined positions in said housing, and an arm mounted on said housing in a predetermined position, said arm having a dished portion which is adapted to fit over the lug carried by said photographic apparatus for positioning said housing with respect thereto, a threaded bore extending into said lug, and a bolt mounted on said arm and adapted to be threaded into the bore of said lug to secure said arm to said lug.

15. A projection device comprising a photographic apparatus having a lug extending therefrom, a threaded bore extending into said lug, two separate objective systems and a turning prism means with a housing therefor, the parts of said optical system being mounted in predetermined positions in said housing, and an arm mounted on said housing in a predetermined position, said arm having a dished portion which is adapted to fit over the lug carried by said photographic apparatus for positioning said housing with respect thereto, and a bolt mounted on said arm, means to yieldingly urge said bolt toward said lug, being thereby adapted to be threaded into the bore of said lug to secure said arm to said lug.

16. In a device for projecting two pictures in superposed relation upon a screen, from a film on which the two pictures appear in pairs, the combination of two completely separate objective lens systems, one for each image, two color filters, one for each of said lens systems, one of said filters having substantially the same color as a Wratten filter No. 28 and the other of said filters having substantially the same color as a Wratten filter No. 38, erecting prism means for turning both images into their upright positions, a mask for each objective lens system positioned along the side thereof which lies adjacent the other lens system, and a septum positioned so as to extend from a point close to the film to a point between the masks and thereby completely separate the image means, said septum being bent at a point between the masks so as to resiliently bear against the opposed surfaces of said masks and close the space therebetween to prevent light from passing therethrough to said prism means, and means to mount said septum for axial movement.

17. In a projection device the combination of two completely separate objective lens systems, means for mounting one of said objective lens systems in a fixed position, means for mounting the other of said objective lens system for movement in a plane normal to the light passing therethrough, eccentric cam means for shifting the movable objective system in two directions substantially at right angles to each other, and clamping means in engagement with said cam shifting means for securing said shifting means in adjusted position whereby to retain said objective lens system in adjusted position.

18. A device for projecting a pair of images which are carried by a transparency on their sides on to a screen in registration, a housing, separate objective systems for focusing each image upon the screen, prism means for erecting said images during projection, separate supports within said housing for said objective systems and said prism means, said support for said prism means being arranged to locate said prism means in a predetermined position within said housing, one of said objective systems being mounted in a support fixed to said prism support to locate said objective in a predetermined position with respect to said prism means, the other of said objective systems being mounted within a support, means to mount said objective support for slidable movement in one plane upon a carriage, means to mount said carriage for slidable movement in another plane on said prism support, said planes lying at right angles, and adjusting means carried by said prism support whereby to adjust said objective system with respect to its companion objective system and to said prism means.

19. A device for projecting a pair of images which are carried by a transparency on their sides on to a screen in registration, a housing, separate

objective systems for focusing each image upon the screen, prism means for erecting said images during projection, separate supports within said housing for said objective systems and said prism means, said support for said prism means being arranged to locate said prism means in a predetermined position within said housing, one of

5 said objective systems being mounted in a support fixed to said prism support to locate said objective in a predetermined position with respect to said prism means, the other of said objective systems being mounted within a support, means to mount said objective support for slid-
10 able movement in one plane upon a carriage, means to mount said carriage for slidable movement in another plane on said prism support, said planes lying at right angles, one adjusting means carried by said prism support and connected with said objective support whereby to
15 adjust said objective system in said one plane with respect to its companion objective system and to said carriage and prism means, and a second adjusting means carried by said prism support and connected with said carriage whereby to adjust said objective system in said other plane with respect to its companion objective system and to said prism means.

20. A device for projecting a pair of images which are carried by a transparency on their 25 sides on to a screen in registration, a housing, separate objective systems for focusing each image upon the screen, prism means for erecting said images during projection, separate supports within said housing for said objective systems and said prism means, said support for said prism means being arranged to locate said prism means in a predetermined position within said housing, one of said objective systems being mounted in a support fixed to said prism support to locate 30 said objective in a predetermined position with respect to said prism means, the other of said objective systems being mounted within a support, means to mount said objective support for slidable movement in one plane upon a carriage, means to mount said carriage for slidable movement in another plane on said prism support, said planes lying at right angles, one adjusting means carried by said prism support and connected with said objective support whereby to adjust said objective system in said one plane with respect to its companion objective system and to said carriage and prism means, a second 35 adjusting means carried by said prism support and connected with said carriage whereby to adjust said objective system in said other plane with respect to its companion objective system and to said prism means, and means carried by said housing for locking both of said adjusting means to retain the movable objective system in adjusted position.

OTTO C. GILMORE.
